UNITED STATES PATENT OFFICE.

JULIUS KRAMER AND ROYAL R. MILLER, OF CHICAGO, ILLINOIS; SAID MILLER
ASSIGNOR TO ADOLPH KARPEN, OF CHICAGO, ILLINOIS.

DAVENPORT-DIVAN.

1,071,757.

Specification of Letters Pat. No. 1,071,757. Patented Sept. 2, 1913.

Application filed April 8, 1912. Serial No. 880,616.

To all whom it may concern:

Be it known that we, Julius Kramer, and Royal R. Miller, citizens of the United States, and residents of the city of Chicago, in the county of Cook and State of Illinois, have invented certain new and useful improvements in Davenport Divans, and we do hereby declare that the following is a full, clear, and exact description of the same, reference being had to the accompanying drawings, and to the number of letters patent marked thereon, which form a part of this specification.

This invention relates to improvements in davenports of that class set forth in the prior application for patent of Royal R. Miller, for "divan beds", executed on the 12th day of March, 1912, and to which reference is made, the drawings of the mattress frame being folded especially upon, and were secured wholly to and secured upon the seat, and in which improved means for supporting and rigidly supporting the seat with its load was provided.

The object of this invention is to improve the means for rotatably supporting the seat, and for releasably engaging the folded mattress frame in folded position.

It is also an object of the invention to afford a construction whereby the mattress frame, when extended, is supported at a higher elevation than possible in the said prior construction.

It is, of course, an object of the invention to afford an exceedingly strong, simple and durable device of the class described, easy to operate and affording a short and firm and secure engagement for the seat when the device is closed, and also for the bed when the mattress frame is fully extended.

The invention (in a preferred form) is illustrated in the drawings, and hereinafter more fully described.

In the drawings: Figure 1 is a top plan view of a device embodying our invention, with the frame partly broken. Fig. 2 is an end elevation of the same, with one of the arms and the cam plate removed, and with the seat in normal position. Fig. 3 is an enlarged similar view, showing the seat inverted preparatory to opening the bed. Fig. 4 is a reduced view similar to Fig. 3, and showing the mattress frame partly extended. Fig. 5 is a similar view showing the mattress frame fully extended. Fig. 6 is an enlarged elevation, illustrating the

relative height, extent and position of the seat when closed with the seat broken away. Figs. 7 and 8 are similar views, illustrating the relative movements of the cam and plunger 10, in opening the seat to its full normal position. Fig. 10 is an enlarged detail view of the cam 3 of Fig. 3. Fig. 11 is a fragmentary view, also enlarged, illustrating the

construction of the mattress frame in full position. Fig. 12 is a fragmentary section taken on line 12-12 of Fig. 10. Fig. 13 is an enlarged fragmentary section taken on line 13-13 of Fig. 9. Fig. 14 is a fragmentary section taken on line 14-14 of Fig. 6. Fig. 15 is a fragmentary detail section on line 15-15 of Fig. 9.

Now, detail at the drawings: the davenport frame consists of end members 1, and back 2, affording the davenport frame. Rigidly secured thereto on each end of said end members 1 is a cam plate 3, comprising a flat cast or stamped to afford near its lower edge a substantially horizontal slot A, extending to near each end of the plate and the lower side or edge of which inclines from its highest point somewhat downwardly to the ends, as shown in Figs. 6 to 9 inclusive. Opening upwardly and forwardly from said slot or cam groove A, and extending obliquely therefrom is a slot B, one wall of which is afforded by a rib 4, integral with the cam plate, being connected therewith by an arched web 5, as shown, affording between the main body of the plate and said web beneath the arched portion, a cam slot C. Said rib 4, is preferably convex on its rear or upper side and the lower end thereof extends to, but not into, the slot A. As shown, the angle of said slot A, afforded between the forward end of slot A, the slot B, and the upwardly and forwardly opening slot C, is rounded or obtuse to facilitate clearance by the locking pin and roller mechanism described.

Rigidly secured on the end member 7, of the seat frame is a pivot plate 8. This extends from a point at the rear of the center of the end of the seat to near the front edge thereof, and rigidly secured theron near its upper and lower edge is a pivot 9, on which is secured a flanged roller 10, which abuts the groove A, in the cam plate with the flange thereof lying outside said plate, the seat frame member of the davenport, of

60 65

course, being cut away beneath said plate to afford clearance therefor. Secured on said pivot plate near the middle and lower edge thereof, is a locking pin 11, on which is secured a roller 12, which tracks in said groove A, as shown in Figs. 6 to 9, and Fig 13, and serves as a lock for the seat in either of its adjusted positions by engaging beneath the lower end of the rib 4, when the pivot pin 10 and roller are at either end of said slot, and, during the passage of the pivot pin and roller from one to the other end of said slot, acts to ride upwardly in the groove B, and thence downwardly in the groove C, during 15 the inversion of the seat. As shown also, the cam plate is provided at its forward end with an outwardly struck integral hook or 20 detent 13, adapted to receive therein the edge of the pivot plate, as shown in Fig. 7, and said edge is curved upwardly and forwardly to near the extremity to slide thereover during the return of the seat to normal position, and a relatively short straight shoulder 14, is provided at the end of said pivot plate to 25 rest in said detent, as shown in Fig. 6, to afford an additional lock for the seat at normal position.

The mattress frame comprising five articulated sections, is foldable upon said seat 30 when inverted, and at all times, when folded, is supported wholly thereon. Said mattress frame comprises alternate long and short sections, as shown in Fig. 5, and indicated by 16, 17, 18, 19 and 20, and is constructed 35 of angle bars, the ends of the angle bar sections being pivotally engaged together through the webs, while the flanges thereof are arranged to abut, as shown in Fig. 1, so that when the mattress frame is extended, 40 the abutting ends of said sections hold the frame as a whole in a common plane.

As shown, the seat frame is provided on its under side, at each rear corner, with a 45 downwardly extending bracket 15, which, when the seat is inverted, as shown in Figs. 3 to 5 inclusive, projects upwardly and outwardly. Rigidly secured by riveting or other suitable means on the under side of the mattress frame sections 17, are downwardly 50 projecting lugs 21, which may be of any desired length, and which are pivotally engaged on the extremities of said brackets 15, by means of a bolt or pivot pin 22, extending through both, so that, when fully extended, said mattress frame section 17, is elevated a desired extent above the upper 55 end of said bracket.

Rigidly secured at approximately the center of the end of the seat frame and projecting downwardly therefrom, is a grooved 60 guide plate 28, which projects below the seat frame a suitable distance and is provided from a point adjacent the seat frame to the rear end thereof, with a downwardly and forwardly inclining slot D, which, at its

lower extremity, is turned horizontally affording a locking offset in the slot. Secured at each end of the mattress frame section 16, is a pin and roller 24, shown in Figs. 1 and 5, and in dotted lines in Fig. 3, said inclined slot in said guide plate and the position of said guide pin and roller on said mattress frame section 16, being such that when the frame is extended, the turning of the short section 17, to a horizontal position 70 acts to swing the long section 16, upwardly simultaneously thereby moving said pin and roller along the slot and into the short horizontal extension thereof at the extremity of the guide plate to afford a lock. 75

As shown, a downwardly curved bar or pipe, 25, engages at its ends the lug 21, before described, and extends therethrough to afford the pivot in the bracket 15. The second long section 18, is articulated as before described, at its inner end with the outer end of the short section 17, and in a similar manner the outer long section 20, is articulated with the intermediate long section 18, by means of the short section 19, which articulates with both and the said members of which are connected transversely by means of the downwardly curved bar or pipe 26. A foot rail 27, is pivotally supported at the extremity of the outer section, 90 as shown in Fig. 5, to hold the bedding from sliding over the foot of the bed. 95

Pivotally engaged at one end with the short frame section 17, is a link 28, which pivotally engages the upper, shorter end of 100 a lever 29, pivoted on the outer end of the intermediate long frame section, and in a similar manner a link 30, pivotally engages the second short section 19, and engages the short upwardly extended end of a lever 31, 105 fulcrumed near the outer end of the outer frame section. The relative lengths of said links and the extended ends of said levers, are such that when the bed is opened outwardly, as shown in Fig. 5, said levers 29 and 31, are projected down automatically to afford supporting legs for said sections, but when the bed is folded inwardly from the end by substantially rolling the mattress frame inwardly progressively, said legs fold 110 in closed relation, as shown in Figs. 3 and 4. 115

Means are provided for positively locking the mattress frame in folded relation on the seat. For this purpose, spring arms or plates 32, each provided with an inwardly 120 directed hook 33, near its extremity, and an extension 34, for manual engagement. beyond the hook is provided on the seat frame and, when the seat is inverted, extends upwardly upon each side the mattress frame 125 as the same is folded inwardly.

Engaged by metallic straps 35, on the under side of the intermediate long frame sections near the middle thereof, are lateral 130 projections 36, shown as a rod of metal bent

to afford a loop projecting beyond said frame members. Said members are pivotally supported in place so that when the bed is extended, as shown in Fig. 5, the same swing downwardly and cannot injure the person. When the bed frame is rolled up or closed upon the seat, as shown in Fig. 3, however, the operator engages each of said members or projections and swings the same outwardly, as shown, into engagement with the hook 33, as shown in Figs. 3, 10 and 11.

The operation is as follows: When the seat is in normal position, as shown in Fig. 2, the folded mattress frame and the bedding are supported wholly upon the seat and beneath the same, and a fall or front board 38, secured at the front of the seat, as shown in Fig. 2, serves to entirely conceal the mechanism supported behind the same. When it is desired to open the bed, the operator engages the front of the seat frame, and pulling the same slightly forward, lifts the seat with the construction supported thereon, which being approximately balanced upon the pivot pin and roller, may be readily inverted, and as the seat is turned over, the locking pin and roller moves upwardly in the groove B, in the cam plate, the projection 6, being rounded to prevent the locking roller catching thereon at the beginning of the upward movement. The pressure applied in inverting the seat, causes the pivot pin and roller to move outwardly to near the forward end of the slot A, and having passed the highest point therein (at which time the locking roller passes over the upper end of the rib 4, and engages on the opposite side thereof in the groove C), the movement is continued until the locking roller reaches the lower end of the rib 4, permitting the pivot roller to move downwardly to the forward extremity of the slot A, and the pivot roller to engage beneath the end of the rib 4. The seat is now locked in inverted position and cannot be moved except reversely and by first pushing the seat slightly inward to clear the locking roller from the lower end of the rib 4. The latches or projections 36, are now released by pressing on the extended end 34, of the spring hooks, and the outer sections of the bed frame are swung outwardly and downwardly, as illustrated in Figs. 4 and 5, successively and downwardly, thus projecting the legs 29 and 31, into supporting position, as shown in Fig. 5, and acting conjointly as a lever to swing the short sections 17, upwardly, thereby elevating and pushing the long section 16, inwardly, moving the guide rollers upwardly in the inclined groove in the guide plate to the top thereof and into supporting position. In this position the bed is fully extended for use. The foot-board 27, may now be turned up, and, of course, the fall or

front board 38, and the upholstering of the back of the davenport serves as a head-board for the bed to assist in holding the bedding in place. The closing of the bed is effected in the same manner, the sections folding or rolling inwardly, and, as the same swing past the position shown in Fig. 4, the short section 17, swings to substantially the position shown in Fig. 3, thus drawing the long section 16, outwardly and downwardly to a position close against the seat frame. The projections 36, are again engaged upon the spring hooks, and the seat may be returned to normal. During the return to normal position, the edge of the pivot plate engaging in the hooked détent afforded on the front end of the cam plate, is guided thereby and substantially locked from any movement away from said cam plate.

Of course, we appreciate that numerous details of the construction may be varied. We have illustrated and described but a preferred construction, and we therefore do not purpose limiting the patent to be granted on this application otherwise than necessitated by the prior art.

We claim as our invention:

1. In a folding davenport bed the davenport frame, the seat, a grooved cam plate secured on said frame centrally of each end thereof, an inwardly projecting, upwardly opening hooked détent at the forward end of the cam plate, a pivot plate secured on each end of the seat, a pivot pin projecting therefrom near the middle of the seat end, a roller journaled thereon and fitting in one of the grooves of the cam plate, and a locking roller journaled on the pivot plate at a distance from said pivot pin and adapted to positively engage beneath a part of the cam plate at each of the adjusted positions of the seat, a sectional mattress frame pivotally engaged by one of its sections on the rear of the seat, an inwardly hooked spring détent projecting downwardly from the seat near the pivot pin, projections on the outer of the mattress frame sections when folded, adapted for engagement by said détents whereby the bed is wholly supported upon the seat, and a foot rail pivoted on the end section of said frame adapted to retain the bedding thereon.

2. In a revolving seat davenport the davenport frame and the seat frame, a mattress frame mounted on said seat frame, a foot rail thereon, a cam plate centrally secured on each end of the seat frame, a pivot plate complementally secured on the davenport frame to exact therewith, a pivot roller and a locking roller journaled on the pivot plate, the one for the pivot roller and others for the locking roller, a rib or projection on the cam plate between the grooves for the locking roller and affording a stop for said

4
roller to lock the seat in normal upright position and when inverted, an upwardly hooked detent integral with one of said plates near the extremity thereof, and receiving a curved end and edge of the other plate therein to afford a guide, and a shoulder beyond said curved portion of said plate adapted for engagement in the detent when the seat is at normal.

10 3. In a revolving seat davenport the davenport frame and the seat frame, a cam plate centrally secured on each end of one of the same, a pivot plate complementally secured on the other to coact therewith, a pivot roller and a locking roller journaled on the pivot plate, the one for the pivot roller and others for the locking roller, a rib or projection on the cam plate between the grooves for the locking roller and affording a stop for said roller to lock the seat in normal upright position and when inverted, an upwardly hooked detent integral with one of said plates near the extremity thereof and receiving a curved end and edge of the other plate therein to afford a guide, a shoulder beyond said curved portion of said plate adapted for engagement in the detent when the seat is at normal, a mattress frame comprising five articulated sections connected with the rear side of the seat frame at its second section, a plate having an inclined groove therein secured on, and projecting downwardly from each end of the seat frame, a roller journaled centrally on each side member of the first mattress frame section and engaging in said inclined groove, and acting to elevate said section thereon when the bed is extended, automatically acting legs on the outer sections, said mattress frame being articulated to roll upwardly and inwardly upon the inverted seat, a foot rail pivoted on said outer sections adapted to fold over the mattress to retain the same and an inwardly hooked spring detent engaged on the under side of the seat frame and adapted to engage the outermost mattress frame section when closed, and to support the same when the seat is at normal.

4. In a device of the class described the davenport frame, the rotatable seat therein, a bracket at each rear corner of said seat projecting downwardly and rearwardly therefrom, a mattress frame comprising articulated alternate long and short mattress frame sections, a foot rail movably mounted on the end sections thereof to retain the mattress thereon, a downwardly projecting lug secured on the first short frame section at each end thereof and pivotally engaged on the extremity of said brackets, a guide plate having a forwardly

and downwardly inclined slot therein communicating with the horizontal slot at the lower end of the same, said guide plates secured centrally at each end the seat frame, 65 and a roller journaled centrally on each end member of the first mattress frame section and projecting into said inclined slot whereby as the mattress frame is extended outwardly or unfolded, the thrust of the first short mattress frame section on the first long section acts to force the same upwardly 70 into a common plane with the mattress frame as a whole.

5. In a device of the class described the davenport frame, the rotatable seat mounted therein, means permitting rotation thereof, locking means holding said seat in its adjusted position both at normal and when inverted, a mattress frame comprising a plurality of long and short articulated frame sections, a pivoted foot rail on the outer long section standards on the rear edge of the seat frame, projecting lugs on the under side the ends of the first short section, a 80 journal on said standards, inwardly hooked spring detents secured one at each end of the seat frame, and a latch hingedly connected with the second long frame section at each end thereof and adapted for engagement with said detent when closed, together with said standards, to wholly support the folded mattress frame on the seat.

6. In a device of the class described a mattress frame comprising alternate long and short articulated sections, adapted to be folded or rolled upwardly and inwardly from the outer end together with its mattress, a foot rail section pivoted on the outer section of the mattress frame to fold over the mattress to retain the same as said sections are folded, brackets rigidly secured on the seat with which the second section of the mattress frame is connected, means elevating the mattress frame well above said bracket embracing a projection on said sections affording the connection between the standard and the same, detents, one at each end of the seat frame comprising inwardly directed hooks, and projections or latches hingedly engaged on the outer mattress frame section when folded, and adapted to engage said detents and together with said standards to support the mattress frame on the seat.

In testimony whereof we have hereunto subscribed our names in the presence of two subscribing witnesses.
